UNITED STATES PATENT OFFICE.

MICHAEL CUMMINS AND LOUIS GREENWALD, OF LEADVILLE, COLORADO; SAID CUMMINS ASSIGNOR, BY DIRECT AND MESNE ASSIGNMENTS, TO JOSEPH LINDSAY AND SAID GREENWALD, OF SAME PLACE.

NECKTIE-FASTENER.

SPECIFICATION forming part of Letters Patent No. 437,578, dated September 30, 1890.

Application filed February 12, 1890. Serial No. 340,095. (No model.)

To all whom it may concern:

Be it known that we, MICHAEL CUMMINS and LOUIS GREENWALD, citizens of the United States, residing at Leadville, in the county of

5 Lake and State of Colorado, have invented a new and useful Necktie-Fastener, of which the following is a specification.

The invention relates to improvements in necktie-fasteners.

10 The object of the present invention is to provide a necktie-fastener of simple and inexpensive construction, adapted to be readily secured to and concealed within the folds of a necktie, and capable of securely holding the 15 neck piece or band and of readily releasing the same when pressed upon externally.

The invention consists in the construction and novel combination and arrangement of parts hereinafter fully described, illustrated 20 in the accompanying drawings, and pointed out in the claim hereto appended.

In the drawings, Figure 1 is a rear view of a necktie provided with a fastener constructed in accordance with the invention. Fig. 2 is a 25 perspective view of the fastener. Fig. 3 is a longitudinal sectional view. Fig. 4 is a transverse sectional view.

Referring to the accompanying drawings, 1 designates the casing which is constructed of 30 metal and is approximately rectangular in cross-section, and is provided at one end with series of perforations 2, by means of which the casing is sewed to a necktie or cravat within the folds of the same, and the upper edge, 35 which is perforated as described, is cut off diagonally to conform to the upper edge of the necktie or cravat, the casing being in most instances arranged diagonally across the necktie. The neck piece or band 3 is passed 40 through the casing 1, and is engaged by a plate 4, having one end secured to the side 5 of the casing and its other end provided with a loop 6, that extends around the side 7 of the casing and is engaged by a spring 8, which 45 holds the edge of the plate 4 in contact with the side 7 of the casing and in position to en-

gage the neck piece or band 3 and hold the same. The edges 9 and 10 of the plates 5 and 7 project slightly beyond the casing, the former being perforated and the latter being 50 adapted to engage the slightly-bent edge of the plate 4, which portions are adapted to clamp the neck piece or band 2. The spring 8 is secured to the top of the casing, has its free end arranged in the loop 6, and is adapted 55 to hold the clamping-jaws or portions formed by the ends of the plate 4 and side 7 together; and it will readily be seen that when it is desired to release the neckband and enable it to be drawn tighter or to be removed from 60 the fastener it is only necessary to press upon the latter, which will compress the spring and carry the plate 4 away from the side 7 of the casing.

From the foregoing description and the accompanying drawings the construction, operation, and advantages of the invention will 65 readily be understood.

What we claim is—

A necktie-fastener concealed within the 70 body of the tie, having the neckband passing therethrough, and being operated by external pressure upon the tie, said fastener consisting of the elongated rectangular casing 1, open at the ends only and through which 75 the end of the neckband passes, and the clamping-plate 4, arranged longitudinally within the casing along one side of the same and adapted to engage the band, the loop 6 connected with the plate, and the externally-80 operated spring arranged upon the outside of the casing and connected with the loop, substantially as described.

In testimony that we claim the foregoing as our own we have hereto affixed our signatures 85 in presence of two witnesses.

MICHAEL CUMMINS.
LOUIS GREENWALD.
